US0D1025005S

(12) **United States Design Patent** (10) Patent No.: **US D1,025,005 S**
(45) Date of Patent: ** Apr. 30, 2024

(54) **NECK SPEAKER**

(71) Applicant: **Roland Corporation**, Shizuoka (JP)

(72) Inventors: **Teruyoshi Kobayashi**, Shizuoka (JP);
Andrea Grecucci, Shizuoka (JP)

(73) Assignee: **Roland Corporation**, Shizuoka (JP)

(**) Term: **15 Years**

(21) Appl. No.: **29/839,334**

(22) Filed: **May 20, 2022**

(51) LOC (14) Cl. **14-01**

(52) U.S. Cl.

USPC **D14/192**; D14/205

(57) **CLAIM**

The ornamental design for a neck speaker, as shown and described.

DESCRIPTION

FIG. 1 is a perspective view of a neck speaker showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, showing the state while in use.

The broken lines shown in FIG. 8 are included for the purpose of illustrating environmental structure and form no part of the claimed design.

1 Claim, 7 Drawing Sheets
